UNITED STATES PATENT OFFICE.

WILLIAM EVERETT VER PLANCK AND HENRI G. CHATAIN, OF ERIE, PENNSYLVANIA,
ASSIGNORS TO GENERAL ELECTRIC COMPANY, A CORPORATION OF NEW YORK.

SYSTEM OF ENGINE-COOLING AND CAR-HEATING.

1,118,601.

Specification of Letters Patent.

Patented Nov. 24, 1914.

Application filed May 13, 1912. Serial No. 896,976.

To all whom it may concern:

Be it known that we, WILLIAM E. VER PLANCK and HENRI G. CHATAIN, citizens of the United States, residing at Erie, county of Erie, State of Pennsylvania, have invented certain new and useful Improvements in Systems of Engine-Cooling and Car-Heating, of which the following is a specification.

10 The present invention relates to motor cars in which an internal combustion engine is employed for propelling purposes, and more especially to such cars where the engine drives an electric generator and the latter supplies current to motors mounted on one or more of the car trucks. The engine and generator are mounted in the front end of the car, the remainder being devoted to passengers, baggage, etc. In such an equipment a means must be provided for dissipating the heat of the circulating water of the engine both in cold and hot weather. It is also necessary to provide a means for heating the car in cold weather. The principal problems presented are first, to effectively cool the engine circulating water; second, to properly heat the car during cold weather and third to prevent the circulating water from freezing in the radiator or pipes or parts connected therewith when the engine is idle.

In carrying out our invention, the engine is provided with a suitable jacket to permit of the circulation of cooling water and this is connected by flexible pipes or hose of large diameter to a radiator that is mounted on and conforms to the shape of the roof as nearly as possible. Such an arrangement has the advantage that a very large surface area for cooling may be provided; that the radiator is located in a position where it is practically free from danger of injury; that it is out of the path of dust and dirt, and is subjected to the maximum effects of the cooling currents of air when the car is in motion. A heater is also provided having a coal fire or other source of heat for heating water that is circulated through heating coils located in the various compartments of the car.

In order to prevent the water in the radiator from freezing in cold weather when the engine is idle, means must be provided for heating the circulating water and in this connection it is to be noted that the prob-

lem is a serious one since the radiator having been purposely designed to dissipate heat of the circulating water as rapidly as possible will similarly dissipate heat from whatever source it may be received. It is also necessary to keep the water in the heating coils in the car itself from freezing. To this end what may be termed a double system is provided that may or may not be interconnected as conditions require. Under running conditions the hot circulating water rises by convection to the radiator, is cooled therein and flows back to the lower end of the cooling jacket of the engine cylinder. The heater contains a coil of pipe or other means filled with hot water, said pipe or means being connected to an expansion tank located on the car roof and to the heating coils in the car itself.

Assuming now that the car is to be left in a cold place with the engine shut down: This means that whereas there were two sources of heat available there is only one now, i.e., the heater. As before stated the cooling and heating systems may be interconnected. Therefore by manipulating valve means located in the piping the cooling system is switched into circuit with the heater and the latter then supplies heat to both of said systems. We have been able to obtain the best heating effects by so arranging the heater that under these conditions the several parts to be heated are connected in multiple with the coil or other heat supplying part of the heater. The multiple arrangement has the advantage of decreasing the resistance to flow of the water and permitting the utilization of the same expansion tank. It also enables us to avoid the expense of a circulating pump and the cost and troubles incident to its upkeep. As an additional means for preventing the rapid radiation of heat from the radiator it may be covered by canvas or equivalent material.

In order to further improve the cooling and heating systems of the engine by reducing the resistance to flow of the cooling water and thereby increasing its effective action, the cooling jackets of the engine are divided into two groups, each being connected to its own radiator, said radiators being interconnected by an overflow tank. For the same reason the heating coils in the car are divided into right and left-hand

groups, each receiving hot water from separate heating coils in the heater, both of said groups utilizing the same expansion tank.

Other features of our invention will be more fully described hereinafter.

In the accompanying drawings, which illustrate one of the embodiments of our invention, Figure 1 is a diagrammatic view of the heating and cooling systems; Fig. 2 is a view partly in section and partly in elevation of an indicator to show the level of water in the radiator; Fig. 3 is a sectional view showing one of the headers and the overflow tank; and Fig. 4 is a detail view showing the arrangement of conduits for conveying water to and from the cooling jackets of the engine cylinders.

Referring to Fig. 1, 10 indicates the floor of the cab containing the apparatus, 11 the side wall thereof and 12 the roof. 13 indicates the main internal combustion engine for propelling the vehicle. It is provided with cylinders 14 and 15 arranged in sets of four each. 16 indicates a small internal combustion engine for driving a generator for lighting the car, and driving an air pump, the latter supplying compressed air for starting, braking, etc. 17 indicates a heater of any suitable construction having a burner 18 of any desired character for supplying heat to the heating coils. 20, 21, 22 and 23 indicate heating coils located in different parts of the car for heating purposes. These coils are divided into two groups or sets arranged on opposite sides of the car. In the present illustration the left-hand coils 20 are supplied with hot water from the heating coil 24 and the right-hand coils 21, 22, 23 with hot water from the coil 25. 26 indicates an expansion tank located above the roof of the car to which the coils 24 and 25 are connected by the pipes 27 and 28. 29 indicates the pipe leading from the expansion tank to one end of the heating coil 20, and containing a cross valve 30 which normally closes the pipe 31 leading to the upper left-hand header of the radiator 32. When the heating system is operating independently of the cooling system this cross valve is closed, and when the heating system and the radiator are interconnected the valve is opened. 32a indicates the pipe leading from the expansion tank 26 to the right-hand heating coils 21, 22, 23. In this pipe is a cross valve 33 which closes the pipe 34 leading to the right-hand upper header of the radiator when the heating system on the right-hand side of the car is operating independently of the cooling system. 35 indicates the return pipe from the right-hand heating coils to the heater 17, and 36 the return pipe of the left-hand heating coils 20 leading to the heater 17. In order to fill the left-hand heating coils 20 and 24 a valved connection 37 is provided to which a

hose can be attached. The right-hand set of heating coils and coil 25 in the heater can be filled by the valved connections 38 or 39 as desired.

The radiator comprises two principal sections, one on the right-hand side and the other on the left-hand side of the car, said radiator being located above the roof and corresponding approximately in shape to the curvature thereof. One of these sections is associated with the set of engine cylinders 14 and the other with the set of engine cylinders 15. Each section is provided with a header 41 located at approximately the center of the car roof, and a smaller header 42, located near the side of the car. Connecting these headers are outer tubes 43 and inner tubes 44. Only two of those tubes are shown, but it is to be understood that a multiplicity of such tubes are provided. Cooling water after leaving the engine flows from the upper header 41 to the lower header 42. Each of the tubes is provided with radiating fins 45 to increase the effective radiation thereof. The lower header is connected by a flexible pipe, such as a piece of hose 46 with the jackets of the engine cylinders. It is necessary to provide a flexible connection at this point on account of the fact that the engine 13 has a certain limited amount of movement independently of the car body.

In Fig. 4 the engine cylinders 14 are shown in side elevation. They are provided with jackets of any suitable construction and circulating water is admitted thereto by the vertical pipe 47 and the horizontal pipes 48 and 49. 50 indicates a pipe that connects the casing of the exhaust valves. The pipes 47 are united by the conduit 51 made in the form of a Y, and to which the pipe 46 is connected. The circulating water is discharged from the jacket by the conduits 52 and 53, which are connected to conduit 54 also made in the form of a Y. This conduit is connected by a pipe of rubber hose 55 with the header 41, Fig. 1. Referring to this latter figure, the arrows indicate the direction of flow of the circulating water through the jackets. 56 indicates a pipe that forms a downward continuation of the conduit 47, and which is connected with the filling connection 57 that is under the control of valve 58. Said connection 57 can be used either for filling the cylinder jackets and the radiator or for draining them by opening the valve 58. The pipe 56 is also connected to the return pipe 36 leading to the heater 17, and contains a valve 58a, said valve being closed when the heating and cooling systems are operated independently. 59 indicates an equalizing pipe for the engine jackets. This contains a valve 60. When the valve is opened the water levels in the parts of the radiator will be equalized through this connection. When the valve 60 is closed one

set or group of engine jackets can be cut out of service. Such an arrangement is desirable when for any reason one section of the radiator is injured or something happens to the operating mechanism of one-half of the engine. In other words, this permits of a partial operation of the car instead of a total failure, as would be the case if the cooling system entirely failed. The jackets, 5 ducts and radiator section on the right-hand side are of the same construction as those on the left-hand side, and hence further description on this point seems unnecessary.

In order to ascertain the level of the water 15 in the expansion tank 26, two overflow pipes 61 and 61^a are provided, the former being somewhat shorter than the latter. These pipes are provided with valves 62 and 63 and both discharge into a funnel 64, the 20 latter discharging through a pipe to a point below the floor of the cab. Under the normal operating conditions the water level should be between the upper end of the pipe 61 and that of 61^a. On opening valve 25 63 if no water flows from the pipe 61, the operator knows that the level is too low. On the other hand if on opening valve 62 water flows through pipe 61^a he knows that the level is too high.

30 The small engine 16 is provided with a cooling jacket 65 which is connected at its lower end by a pipe 66 to the radiating system on the right-hand side of the main engine, and its upper end is connected with a 5 pipe 67 to a pipe 34, leading to one of the headers of the radiator.

Referring to Fig. 1 when the heating and cooling systems are operating independently the valves 30, 33 and 58^a are closed. When, 40 however, the engine is shut down and it is desired to operate the two systems simultaneously from the heater these valves are opened and hot water flows from both coils 24 and 25 of the heater 17 through the pipes 27 and 28 to the expansion tank 26 and thence through pipes 29 and 32^a to the car 45 heating coils 20, 21, 22 and 23, returning by pipes 35 and 36 to the coils of heater 17. In addition to this hot water flows through 50 valves 30 and 33 into the vertical pipes 31 and 34 opening into the upper headers 41 of the radiator. From these headers the hot water flows downward through pipes 55 to both sets of cylinder jackets. After passing 55 through the jackets the water is returned to the coils of the heater by pipes 56 and pipes 35 and 36, these latter communicating with the heating coils 24 and 25. Under these conditions valves 58^a and 89 must be open. 60 Hot water also flows from the upper headers 41 through the radiator tubes 43 and 44 to the lower headers 42 from which it flows by the rubber hose or pipes 46 to the lower ends of the engine jackets and discharges 65 into the pipes 56 which return the water

from the engine jackets to the coils 24 and 25 of heater 17 as before stated. Hot water also flows from the pipe 34 leading to the header 41 by pipe 67 to the jacket of the small engine from which it is returned 70 to the main supply by the pipe 66.

By the above arrangement it will be noted that when the engine is shut down one set of cooling jackets and radiators is connected in with each car heating coil, the jackets, 75 radiator and heating coil on each side being in parallel with each other. By closing off one of the valves 58^a the valve 60 being open, we can connect both sets of engine cylinders and radiators to a single one of 80 the heating coils. Such an arrangement might prove desirable, as for example, in case one of the coils of the heater was burned out.

In order to avoid the danger incident to 85 low water in the radiator an indicator is provided of the character shown in Fig. 2, in which 75 indicates a tubular chambered member containing a body of water. Supported by the water is a hollow metal float 90 77 that is connected to a tube 78. Located within this tube is a second tube 79 which rises considerably above the maximum predetermined level of the water. Extending 95 through the tube 79 and attached to the outer tube 78 is a small rod 80 to the lower end of which is attached an indicator 81 that by comparison with a flat plate 82 indicates the position of the float 77 in the float chamber, and therefore the level of 100 the water therein. Preferably the plate 82 is painted with different colors so that the attention of the operator may be more readily attracted, particularly when the water is getting low. As shown the tubular member 75 extends upwardly through the header 41, and also through the overflow tank 83 which is mounted on top of the header. 43 and 44 indicate the tubes extending from the upper to the lower header. The lower 105 end of the tubular member 75 is perforated at 84 to permit water to enter the float chamber from the water chamber 85 of the header. A guard 86 is also provided, which stands in front of the opening 84 and acts 110 to prevent the movement of the water in the chamber 85, due to car movements, from directly affecting the float.

Referring to Fig. 3, we have shown one 115 of the headers, 41 in longitudinal section. In order to further improve the operation of the cooling system an overflow tank 83 is provided whose cubical contents is preferably a little bit greater than that of the water jackets of the engine, so that in the event of the engine becoming over heated, and causing steam, an amount of water equal to the contents of the jackets may be discharged from the headers into said overflow tank. The transfer of water from one tank 125

to another takes place through the openings 87. This overflow tank is also useful when the car is climbing a steep grade because water that might otherwise run out of the radiator through one of the filling holes at the top is caught in said tank and returned to the radiator as soon as the conditions become normal.

At certain seasons of the year only a comparatively small amount of heat is required in the car for limited periods of time and under such conditions the heat of the engine or engines may be utilized in supplying hot water to the car heating coils. Referring to Fig. 1, a valve 88 is placed in the pipe 46 leading from the radiator to the engine. A second valve 89 is placed in the pipe 36 leading to the heating coil 24 to cut it out of service, the burner of course being out of action. Similar arrangements should be provided for the right-hand side of the system. To utilize the heat from the engine the valve 88 is wholly or partially closed depending upon conditions and the valve 89 is shut. Hot water from the engine will now flow to the header 41, thence through pipes 31 and 29, through the coil 20 and valve 58 back to the engine. If the valve 88 is partially open some water will flow through the radiator and return to the engine. The amount that this valve is opened will be determined by the temperature of the engine, care being exercised not to overheat it.

In accordance with the provisions of the patent statutes, we have described the principle of operation of our invention, together with the apparatus which we now consider to represent the best embodiment thereof; but we desire to have it understood that the apparatus shown is only illustrative, and that the invention can be carried out by other means.

What we claim as new and desire to secure by Letters Patent of the United States, is,—

1. In combination, an engine, an inclosure therefor, a cooling system for the engine that extends outside of the inclosure, a water-circulating heating system that is normally independent in its operation of the cooling system and is located within the inclosure, and valved means for connecting the cooling system in multi-relation to the heating system and disconnecting it therefrom.
2. In combination, an engine having a cooling jacket, a radiator for dissipating the heat of the fluid circulating through the jacket, a water-circulating heating system having a heater that is normally disconnected from the jacket, said system operating independently of the cooling system of the engine, and valved means for connecting the jacket and radiator to the heater in multiple with the heating system when the engine is shut down.

3. In combination, an engine having a cooling jacket, an inclosure for the engine, a radiator located outside of the inclosure, conduits connecting the jacket and the radiator, a water-circulating heater located inside the inclosure and operating independently of the cooling system of the engine, heating coils connected therewith, and valved means for connecting the radiator to the heater in multiple with the heating coils to impart heat to the fluid passing therethrough.

4. The combination with an engine having a cooling system comprising a cooling jacket, a radiator, and conduits connecting the jacket with the radiator, and a heating system comprising an expansion tank, a heater, and heating coils connected with the heater and expansion tank, said systems being normally independent in operation, of valved connections between the engine jacket and an inlet to the heater whereby said jacket may be connected to the heater.

5. In combination, an engine having cooling jackets divided into groups, a radiator, conduits connecting each of the groups to the radiator, heating coils also arranged in groups, the flow of liquid through the engine jackets and heating coils being normally independent, a heater for supplying hot water to the groups of heating coils, and means for connecting the groups of engine jackets and the radiator with the heater when the engine is shut down.

6. In combination, an engine, each cylinder of which is provided with a water jacket, connections connecting the jackets in multiple as regards the flow of cooling water, a radiator, conduit means that conveys water from all of the jackets to the radiator, a second conduit means that receives water from the radiator and supplies it in multiple to all of the engine jackets, a heater, a water-circulating heating system connected thereto, and means for connecting the jackets and the radiator to the heating system in multiple therewith.

7. In combination, a vehicle, an engine for propelling the same, an air cooled radiator mounted on the roof of the vehicle for dissipating the heat of the fluid circulating through the jackets of the engine, a heater located within the vehicle, a water-circulating heating system connected thereto, fluid carrying connections that unite the heater with the radiator in multiple with the heating system, and valves in the connections which are normally closed but are opened when it is desired to connect the radiator to the heater to prevent the water therein from falling below a predetermined temperature.

8. In combination, an engine having cooling jackets arranged in sets, a divided radiator to which the jackets are connected by pipes, a heater operating independently of the engine, groups of heating coils arranged

- to receive heated fluid from the heater, an expansion tank that is common to the heating coils, valve means for connecting and disconnecting the cooling jackets and radiator from the heater and tank, and a pipe for equalizing the level of fluid in the parts of the radiator.
9. In combination, a vehicle, heating coils therefor, a heater for supplying fluid to the coils, an internal combustion engine which has a fluid cooling system that normally operates independently of the heater, and valved means for disconnecting the heater from the coils and connecting the fluid cooling system of the engine thereto.
10. In combination, a vehicle, an engine having cooling jackets arranged in sets, a divided radiator to which the jackets are connected by pipes, a heater having a plurality of separate coils, vehicle heating coils connected with each heater coil, and valved means for connecting a set of cooling jackets to each of the heater coils.
11. In combination, a vehicle, an engine having cooling jackets, a radiator, pipes connecting the cooling jackets thereto, a heater having a plurality of separate coils, vehicle heating coils connected with the heater coils, and valved means for connect-
- ing the cooling jackets to one of said heater coils.
12. In combination, a vehicle, an engine having cooling jackets arranged in sets, a divided radiator to which the jackets are connected by pipes, a heater having a plurality of separate coils, vehicle heating coils connected with each heater coil, and valved means for connecting a division of the radiator to each of the heater coils.
13. In combination, a vehicle, an engine having cooling jackets arranged in sets, a divided radiator to which the jackets are connected by pipes, a heater having a plurality of separate coils, vehicle heating coils connected with each heater coil, and valved means for connecting a set of cooling jackets and a division of the radiator to each of the heater coils.

In witness whereof, WILLIAM E. VER PLANCK has hereunto set his hand this 18th day of April, 1912, and HENRI G. CHATAIN has hereunto set his hand this 11th day of May, 1912.

WILLIAM EVERETT VER PLANCK.
HENRI G. CHATAIN.

Witnesses:

HELEN ORFORD,
BENJAMIN B. HULL.

It is hereby certified that in Letters Patent No. 1,118,601, granted November 24, 1914, upon the application of William Everett Ver Planck and Henri G. Chatain, of Erie, Pennsylvania, for an improvement in "Systems of Engine-Cooling and Car-Heating," an error appears in the printed specification as follows: Page 2, line 83, for the word "those" read *these*; and that the said Letters Patent should be read with this correction therein that the same may conform to the record of the case in the Patent Office.

Signed and sealed this 5th day of January, A. D., 1915.

[SEAL.]

R. F. WHITEHEAD,
Acting Commissioner of Patents.
